UNITED STATES PATENT OFFICE

RICHARD F. SMITH, OF CHARLESTON, SOUTH CAROLINA, ASSIGNEE, BY DIRECT AND MESNE ASSIGNMENTS, OF ONE-FOURTH TO RAYMOND D. SULLIVAN, OF PORTSMOUTH, VIRGINIA, AND ONE-HALF TO CHARLESTON DRY DOCK AND MACHINE COMPANY, OF CHARLESTON, SOUTH CAROLINA, A CORPORATION OF SOUTH CAROLINA

SHIP HULL CONSTRUCTION

Application filed April 23, 1929. Serial No. 357,586.

My invention relates to ships and more particularly to an improved hull construction whereby the usual transverse frame members and longitudinal beams are united without the use of rivets or other similar fastenings.

An object of the invention is to provide a ship hull construction having lock joints between the transverse frame members and the longitudinal beams whereby the transverse frame members will be drawn into correct position and held in this position upon assembling the beams therewith.

A further object of the invention is to provide an improved lock joint between the transverse frames and longitudinal members which may be quickly assembled by the workmen and subsequently spot welded to hold the parts in proper relation.

A still further object of the invention is to provide an improved ship hull construction in which a series of peripheral openings in each of a plurality of transverse frames are arranged to match longitudinally and to sustain connecting rods that are of a length to reach from stem to stern of the ship so that the chief effort of the workman will be to slide them longitudinally in getting them in place.

It is another object of the invention to provide a ship hull construction which in addition to rendering the hull lighter in weight than ships of modern construction provides a more rugged structure at a minimum cost.

With the preceding and other objects and advantages in mind, the invention consists in the novel combination of elements, constructions and arrangements of parts and operations to be hereinafter more fully described, claimed and illustrated in the accompanying drawings, wherein:

Figure 1 is a side elevation of a ship constructed in accordance with my invention and having one of its side walls thereof partially broken away;

Fig. 2 is an enlarged vertical section taken on line 2-2 of Fig. 1;

Fig. 3 is a fragmentary perspective of one of the improved transverse frame members;

Fig. 4 is a perspective of one of the longi-

tudinal beams for assembly with the frame disclosed in Fig. 3;

Fig. 5 is a fragmentary perspective of the hull and illustrating the longitudinal beams assembled with one of the transverse frame members;

Fig. 6 is a fragmentary perspective of a modified embodiment of the transverse frame member;

Fig. 7 is a fragmentary perspective of a longitudinal beam for use with the frame member disclosed in Fig. 6; and

Fig. 8 is a fragmentary detail view partly in section and partly in elevation of the parts disclosed in Figs. 6 and 7 in assembled relation.

Referring to the invention in detail and particularly to the structure disclosed in Figs. 1 to 4 inclusive a ship hull 5 whose skeleton frame is made up of a plurality of 70 spaced transverse frame members 10 and longitudinal bars 11 is provided.

For the purpose of uniting the frame members 10 and bars 11 without the use of rivets and other similar fastenings I provide 75 an improved lock joint at predetermined points along each of the longitudinal bars and the outer edge of each transverse frame member. The joint consists of a slot 12 in the transverse frame member which opens 80 upon the outer edge of the latter and is of a length corresponding to the width of the bars 11 so that the outer longitudinal edge of the bars will lie flush with the outer edges of the transverse frame member. A rectangular notch 13 is formed in the inner edge of the longitudinal bar, to interlock 85 with the slot 12 when the bar is shifted laterally toward the transverse frame member. This notch 13 is of such depth as to permit 90 the beam to lie within the slot 12 with the outer longitudinal edge of the bar flush with the outer edge of the transverse frame member.

After the bars 11 are assembled with the transverse frame members each lock joint is spot welded as at 17. It will be observed 95 that in assembling the bars with the transverse frame members the opposed walls of the notches 13 will engage the opposite faces 100

of the frame members and draw the same into parallelism and retain them in this position at all times. Thus warping of the skeleton frame is eliminated.

- 5 In Figs. 6 to 8 inclusive a modification of the lock joint is disclosed. In this form of the invention the lock joint consists of an elongated opening 15 which is slightly longer than the width of the bar as particularly 10 illustrated in Fig. 8. In this instance the notch 13 is in the outer longitudinal edge of the bar and is of such depth as to bring the outer edge of the bar flush with the outer edge of the transverse frame member. The 15 bar is slid longitudinally through the elongated opening 15 until the notch 13 is in registration with the end walls of the opening. At this time the bar is shifted laterally in an outward direction to interlock the 20 notch with the outer end wall of the opening. After the parts are interlocked as above stated they are secured in place by spot welding 15. It is pointed out that with this embodiment of the invention the bars 11 are 25 easy to handle. That is to say, the weight of the bars is sustained by the walls of the elongated opening 15 and no other manual exertion is necessary than to shift the bars laterally to cause the lock joint to interlock 30. The usual shell plating 16 extends around the skeleton frame and as disclosed in Fig. 5 the individual plates lie upon the outer edges of the bars 11. The adjacent ends of these plates are welded to the beams as 35 at 17.

The operation is as follows:—In the erection of the hull of a boat the successive transverse frames 10 are stood in the approximate spaced positions and temporarily held there 40 either by bars running along the tops or by deck plating. Although these transverse frames are usually rather heavy they are, nevertheless so comparatively flimsy that a workman taking hold of one of them can 45 sway them with utmost ease.

In order to at once fix these transverse frames so firmly that absolutely no swaying can be perceived as well as to utilize these transverse frames as the anchorages for the 50 longitudinal bars 11, both the transverse frames 10 and the longitudinal bars 11 are provided with the matching notches 12, 13 (Figs. 3 and 4), which when fitted together at once establish the contour of the boat 55 in skeleton form.

It is of especial note that the longitudinal bars 11 run from stem to stern of the boat. There is no break in these longitudinals. In order that they may properly fit their 60 assigned places in the modeling of the ship, they are first accurately developed in the shop, in other words, the notches 13 (Fig. 4) are first located and cut with that accuracy that will insure the perfectly upright and 65 unwavering anchoring of the transverses 10

when the longitudinal beams 11 are set in place.

Having once set one of the longitudinal bars 11 in place the welder will temporarily secure the joint by tack-welding at each pair of slots 12, 13. Each of the longitudinals is treated in this way until all are tacked in place. Final welding is a subsequent operation.

Another point of note is that bulkheads 75 are connected in the assemblage just as are the transverse frames 10. In other words, there are no breaks in the longitudinal bars 11 even for bulkheads. By making the longitudinal bars continuous from stem to stern it follows that the accurately located notches 13 will be an infallible gauge to the erect positioning of the transverse frames 10. The result is a mutual holding of the transverse frames 10 and longitudinal bars 11. 80 One secures the other in place so that the subsequent welding does not become a matter of conjecture, making it uncertain whether the workman will tack-weld exactly at the right point.

Substantially the same procedure is followed when erecting a ship hull according to the modification in Figures 6, 7 and 8. The additional advantage previously brought out, is that the bars 11 are sustained in the 95 longitudinally matching openings 15 while the workman shoves the bar along until it is fully in place. This relieves much of the effort in lifting the bar into position so that the assembling can be done with a 100 fewer number of workmen.

From this it will be understood that the invention also involves a novel method in the erection of ship hulls. It must be borne in mind that the various transverse frames 10 and longitudinal bars are comparatively heavy. It is obvious that these members are individually heavier as the size of the ship whose hull they comprise parts of increases. Yet notwithstanding the weight of the frames and bars they are capable of being fitted together in a rather temporary manner until the joints are tack-welded to impart a necessary measure of initial security.

The method thereby involves the fitting together of the various transverse frames 10 and the longitudinal bars 11 from stem to stern for an initial mutual support, whereupon tack-welding is resorted to to hold the parts together. When the entire hull is thus put together, the joints are finish-welded in a 115 subsequent operation.

What is claimed is:

1. In a ship hull construction, a plurality of transverse frames each having a series of openings adjoining the outer edge and defining webs, and a plurality of bars extending full-length from stem to stern of the ship, being reeved through the longitudinally matching openings and having notches to fit 125

over the webs to bring the outer edges of the frames and bars flush.

2. In a ship hull construction, a plurality of transverse frames each having a series of 5 openings adjoining the outer edge and defining webs, a plurality of bars extending full-length from stem to stern of the ship, being reeved through the longitudinally matching openings and having notches to fit over the 10 webs to bring the outer edges of the frames and bars flush, and welds to secure the joints between the frames and bars.
